CLAIM

The ornamental design for a medical console, as shown and described.

DESCRIPTION

FIG. 1 is a top, front, right perspective view of a medical console having a main unit and a handset, shown in exploded view for clarity of disclosure;

FIG. 2 is a top, front, right perspective view of the main unit of FIG. 1;

FIG. 3 is a top, rear, right perspective view of the main unit thereof;

FIG. 4 is a top, front, right perspective view thereof;

FIG. 5 is a top, rear, right perspective view thereof;

FIG. 6 is a front elevation view thereof;

FIG. 7 is a rear elevation view thereof;

FIG. 8 is a right side elevation view thereof;

FIG. 9 is a left side elevation view thereof;

FIG. 10 is a top plan view thereof;

FIG. 11 is a bottom plan view thereof;

FIG. 12 is a top, front, right perspective view of the handset of FIG. 1;

FIG. 13 is a top, rear, right perspective view thereof;

FIG. 14 is a top, front, left perspective view thereof;

FIG. 15 is a bottom, rear, left perspective view thereof;

FIG. 16 is a top plan view thereof;

FIG. 17 is a bottom plan rear elevation view thereof;

FIG. 18 is a right side view thereof;

FIG. 19 is a left side view thereof;

FIG. 20 is a front elevation view thereof; and,

FIG. 21 is a rear elevation view thereof.

The broken lines shown in the drawings represent portions of the medical console that form no part of the claimed design.

1 Claim, 21 Drawing Sheets
